ADJACENT CHANNEL SELECTIVITY

William S. Barden, Stapleton, N. Y., assignor to
 Radio Corporation of America, a corporation of
 Delaware

Application November 6, 1931, Serial No. 573,410

11 Claims. (Cl. 250—20)

My present invention relates to adjacent channel selectivity, and more particularly to a method of, and means for, securing such selectivity by great frequency discrimination at radio frequency followed by compensation at audio frequency.

The novel features which I believe to be characteristic of my invention are set forth in particularity in the appended claims, the invention itself, however, as to both its organization and method of operation will best be understood by reference to the following description taken in connection with the drawing in which I have indicated diagrammatically one circuit organization whereby my invention may be carried into effect.

In the drawing,

Fig. 1 is a graphic representation of a portion of the broadcast spectrum,

Fig. 2 diagrammatically represents a superheterodyne receiver including the present invention,

Fig. 3 graphically shows the operation of the radio frequency discrimination means,

Fig. 4 shows the effect of the discrimination means on the conditions shown in Fig. 1,

Fig. 5 graphically demonstrates the characteristic of the audioamplifier of the receiver shown in Fig. 2.

Referring now to the drawing wherein like reference characters designate the same elements in the different figures, there is shown in Fig. 1 a graphic representation of the intensity of desired and undesired signals in the vicinity of a broadcast receiver. Thus, the heavy line A may designate a desired carrier of one unit strength, while the heavy line C, positioned 10 kilocycles away, designates an undesired carrier of the same strength. Each of these carriers is attended by a single side band component of one unit strength, to wit: B and D, spaced at frequencies f and f_0 respectively from the carriers A and C.

These side band components are on such sides of their carriers that side band interference will be a maximum. This should be clear from Fig. 1, where E, in dotted line, represents the side band interference positioned 5 kilocycles from either carrier A and B. It will now be seen that the problem of adjacent channel selectivity is entirely divorced from the problem of interference residing on the desired signalling band. Adjacent channel selectivity is fundamentally a matter of frequency discrimination. But, when the interference and signal reside on all of a common channel, no hypothetical scheme can possibly represent a result which is not in har-

mony with the conventional theory of wave form analysis.

In Fig. 2 there is shown a receiver arrangement which employs side band cutting frequency discrimination with audio compensation of a special type. By means of this arrangement it is possible to solve the problem graphically represented in Fig. 1. Furthermore, this solution involves in no sense doctrines which are in defiance of well-known principles. The frequency discriminator is preferably employed in a radio receiver of the superheterodyne type for the reason that the discriminator employed herein lends itself more readily to such a receiver. As is well known, a superheterodyne receiver, as shown in Fig. 2, comprises the usual grounded antenna A, G coupled, as at M, to the input of a tuned radio frequency amplifier, the latter comprising one or more stages utilizing electron discharge tubes. The amplified radio frequencies are impressed upon the input circuit of a first detector tube, the latter also having impressed upon it the output of a local oscillator. The first detector tube functions as a frequency changing device and produces in its output circuit a carrier of an intermediate, or super-audible beat frequency, having superimposed upon it the audio frequency modulations corresponding to the modulations which were originally carried by the radio frequency carrier. While I have not shown any constructional details up to this point, other than conventional representation, it is to be understood that the usual uni-control tuning arrangements may be employed for selection of desired signals.

The modulated intermediate frequency carrier is impressed upon the input circuit of the first tube of the intermediate frequency amplifier. While the latter usually consists of more than one stage of amplification, each stage including an electron discharge tube, for the sake of simplicity the first intermediate frequency amplifier stage only is shown. This stage includes the electron discharge tube 1 having connected between its cathode and control electrode a so-called crystal bridge. The crystal bridge consists of four arms, three of the arms including capacities C_1 , C_2 and C_3 , while the fourth arm includes a piezo-electric crystal 2 mounted between the electrodes 3 and 4. The piezo-electric arrangement is conventionally shown, those skilled in the art clearly understanding the manner of mounting the crystal between the electrodes 3 and 4.

The point 5 of the crystal bridge is connected

to the high potential side of the capacity 6 and inductance coil 7, the latter two elements comprising a circuit resonant to the intermediate frequency carrier. The point 8 of the crystal bridge is connected to the low potential side of the resonant circuit 6, 7. The remaining two points 9 and 10 are connected to the grid and cathode respectively of the tube 1.

It has been found that the crystal bridge in the input circuit of the first intermediate frequency amplifier tube functions as an extraordinarily great frequency discriminator. Briefly, the capacities C_1 , C_2 , C_3 and the capacity between the electrodes 3 and 4 are so proportioned that no signal potential is applied to the grid of the tube 1 unless energy of the intermediate frequency is impressed upon the resonant circuit 6, 7. That is to say, the crystal 2 has a natural resonance equal to the intermediate frequency impressed, and the crystal bridge is in balance for all frequencies other than this particular intermediate frequency. It will therefore be seen that signal potential is applied to the grid of tube 1 only when the crystal 2 is forced into oscillation by the intermediate frequency energy; in other words the crystal bridge is unbalanced to energize the grid of tube 1 for energy of intermediate frequency only.

Better results are found to be secured by connecting a resistance 11 between the point 9 and the point 10 of the crystal bridge, the grid of tube 1 being normally maintained at a negative bias by the source 12.

In Fig. 3 there is shown graphically the characteristic of the input circuit of the intermediate frequency amplifier, and particularly the extent to which frequency discrimination is carried by the crystal bridge arrangement. In this figure, plotting "Response" against "Frequency", it is seen that the band of frequencies passed by the frequency discriminator is exceedingly narrow, the dotted line I representing the intermediate frequency carrier, while the full line demonstrates the attenuation of frequencies off either side of the intermediate frequency carrier. It will be seen that practically complete attenuation is secured 100 cycles off either side of the intermediate frequency carrier I. In other words, by utilizing the frequency discrimination means shown in Fig. 1, there is transmitted through the intermediate frequency amplifier a band of frequencies of only about 200 cycles in width.

Subjecting the action of the crystal admission circuit disposed between the frequency changing device and the intermediate frequency amplifier to further analysis, assume that the resonator to which the components shown in Fig. 1 are applied has such a low decrement that at 50 cycles off resonance the attenuation is to 10% (i. e. 90% attenuation), and from then on the attenuation is substantially inversely as the extent (absolute) off resonance, then it can be shown that Fig. 4 is a graphic representation of the effect on the component shown in Fig. 1. It will be seen from Fig. 4 that due to the attenuation characteristic of the crystal admission circuit the desired carrier A still possesses one unit strength, while the undesired carrier C, 10,000 cycles off resonance, has been attenuated to .0005 of a unit. Similarly, the side band component D of the carrier C has been attenuated to a similar extent. The interference component E, 5,000 cycles off resonance, has been attenuated to .001 of a unit.

However, it will be observed, additionally, that a side band component B, only 100 cycles off

resonance, which side band component is desired, has been attenuated to .05 of a unit.

The output of the intermediate frequency amplifier is then subjected to the action of a second detector, and the detected output impressed upon an audio frequency amplifier of special design. It has been found that the primary 20 of the audio frequency transformer M_1 should have an inductance of approximately 2 henries. The audio-frequency amplifier has only its first stage shown in detail, it being understood that as many stages as desired can be employed. Of course, those skilled in the art understand that the designation "To utilization means" represents additional audio stages designed in a manner similar to the stage shown in detail, and subsequent headphones or loud speaker, or similar translating means.

The first audioamplifier stage, then, comprises an electron discharge tube 23 having arranged in its output circuit a series resonant path which includes a capacity 21 and an inductance 22. The series resonant path is connected between the anode and cathode of the tube 23 and is tuned to a period of 4800 cycles. It will be understood that if additional stages of audio amplification are employed, each of such stages will have a similar series resonant path in its output circuit. The characteristic of such an audiofrequency amplifier is graphically represented in Fig. 5. In this figure, secured by plotting "Audiofrequency gain" against "Frequency", it is shown that those components least attenuated by the crystal admission circuit are amplified in the compensated audioamplifier to the least extent.

Thus, the carrier component A of Fig. 4 would be amplified to the least extent, the numeral "1" designating the amplification of the component A as of one unit. On the other hand, there is a straight line increase in amplification of the components up to 4800 cycles off resonance, the component at the latter point being amplified 50 units more than the component A. It will be observed that the audio amplifier, by means of the series resonant paths in the plate circuit of each stage possesses a sharp cut-off at 4800 cycles. It necessarily follows that the side band interference component E, which is 5000 cycles off resonance from the desired carrier A, is not amplified because of this sharp cut-off characteristic. It will thus be seen that attenuation of desired audio components by the crystal admission circuit is compensated for by the use of an audio frequency amplifier having a characteristic as shown in Fig. 5, and possessing a sharp cut-off prior to the point in the frequency range where the undesired side band interference is positioned.

However, the utility and desirability of the present invention becomes more evident when a so-called "dynamic" method of determining adjacent channel selectivity is employed. When two signals exist 10 kilocycles apart, cross heterodyne among their side bands, and even between their carriers, as well, brings an entirely different aspect to the problem. The present low-decrement audio compensation system can now be compared from the standpoint of "dynamic" selectivity with the dynamic selectivity of a standard superheterodyne receiver. It can be theoretically demonstrated by the "dynamic" method, that the heterodyne of an undesirable component 5000 cycles off resonance from its carrier with a desirable component ranging from zero to 5000 cycles off resonance from its carrier

is the characteristic of most intense heterodyne, and plainly this response will vary with the number of cycles off resonance of the desirable component, the cross heterodyne being a maximum where the strength of the desirable component off resonance is greatest.

It can be shown, for example, that with the desirable component 4700 cycles off resonance from its carrier, the ratio of desired to possible undesired is 60:1. If the modulation frequency on the undesired signal carrier never exceeded 4700 cycles, the present system would be sixty times as meritable as a conventional superheterodyne receiver which is rated to be flat to 4700 cycles on its fidelity characteristic.

If the undesired signal be modulated intermittently and generally feebly, at about 4700 cycles, the ratio rapidly becomes less favorable, and at 5000 cycles, the side band interference might break through occasionally so as to be noticeable. The chances are remote that it would ever be noticed unless it is being looked for, because during program modulation, in general, only a small percentage of the energy is concentrated near 5000 cycles, and the entire desired program exists to easily overwhelm the undesired effect. Thus, to be extreme, and accomplish the ideal theoretically the undesired signal could be modulated to 5000 cycles, progressively monotone without lowering the 60:1 ratio, the audiocompensation being cut off at audiofrequency below 4700 cycles, thus maintaining substantially ideal legitimate fidelity.

However, it is important to point out that the region of possibly great side band interference is so confined that only a very slight sacrifice in fidelity need be made to eliminate it, and that when not taken care of (i. e. no cut-off in compensator) the situation is not bad, for reasons already stated. It should be clear that when dealing with interference outside of the signalling band, the theory of proportionate loss of fidelity does not hold. Again, it is well to note that in practice the selectivity merit of the present system is four times as great as has been pointed out heretofore.

It has been assumed throughout the present analysis that all side band potentials are concentrated on one side of their carriers. Actually, of course, it would be half on each side of the carrier, and, due to the product principle, (since both desired and undesired components on adjacent sides are halved), the audio developed is one-fourth of what has been shown, thus increasing the ratio by four.

While I have indicated and described one arrangement for carrying my invention into effect, it will be apparent to one skilled in the art that my invention is by no means limited to the particular organization shown and described, but that many modifications may be made without departing from the scope of my invention as set forth in the appended claims.

What I claim is:

1. In combination, in a superheterodyne receiver, a frequency changing device, means for amplifying the changed frequency, a frequency discriminator disposed between the frequency changing device and the amplifier, said discriminator having a frequency response characteristic which decreases rapidly for frequencies off resonance, a second detector, and an audio amplifier having a characteristic inverse to that of the frequency discriminator, the amplifier being provided with means having a sharp cut-off prior

to the point in the frequency range where undesired side band interference is positioned.

2. In a superheterodyne receiver, means for collecting signal energy, means for generating local energy, means for combining the signal and local energies, a crystal admission circuit adapted to transmit a band of frequencies including the desired carrier and its band components, and the circuit transmitting substantially the greater portion of the desired band components greatly attenuated with respect to the carrier, and audio compensation means for amplifying the transmitted components in a manner inverse to their attenuation by the crystal admission circuit, the amplifier being provided with means having a sharp cut-off prior to the point in the frequency range where undesired side band interference is positioned.

3. In a radio receiver, a frequency discrimination circuit of low-decrement adapted to transmit a band of frequencies including the desired carrier and substantially the greater portion of the desired components greatly attenuated with respect to the carrier, and an audio-amplifier including compensation means whereby the amplifier has an amplification characteristic inverse to the discrimination characteristic of the said discrimination circuit, the amplifier compensation means additionally imparting a sharp cut-off prior to the point in the frequency range where undesired side band interference is positioned.

4. In a radio receiver, a crystal admission circuit of low-decrement adapted to transmit a band of frequencies including the desired carrier and substantially the greater portion of the desired components greatly attenuated with respect to the carrier, and an audio-amplifier including compensation means arranged to impart an amplification characteristic inverse to the characteristic of the said admission circuit, said amplifier having a sharp cut-off at 4800 cycles.

5. In a radio receiver, a crystal bridge circuit of low-decrement adapted to transmit a band of frequencies including the desired carrier and substantially the greater portion of the desired components greatly attenuated with respect to the carrier, and an audio-amplifier including compensation means imparting to the amplifier an amplification characteristic inverse to the characteristic of the said bridge circuit, the amplifier additionally having a sharp cut-off prior to the point in the frequency range where undesired side band interference is positioned.

6. A receiver for wave signals comprising a resonant circuit for wanted incoming signal energy, such as is constituted by a modulated carrier wave, a local generator of oscillations to combine with the incoming energy to produce energy of an intermediate frequency, resonant means including a piezo-electric device for transmitting the intermediate frequency energy therethrough, whereby the amplitude of wave-form energy corresponding to different modulation frequencies is varied substantially in inverse proportion to the frequency value, a detector and an audio frequency amplifier, means for varying the amplitude of wave-form energy corresponding to the different modulation frequencies substantially in proportion to the frequency values, the amplifier including in its output means for imparting a sharp cut-off to the amplifier at 4800 cycles.

7. A receiver for wave signals comprising a resonant circuit for wanted incoming signal energy, such as is constituted by a modulated carrier wave, a local generator of oscillations to com-

bine with the incoming energy to produce energy of an intermediate frequency, resonant means including a piezo-electric device for transmitting the intermediate frequency energy therethrough, 5 whereby the amplitude of wave-form energy corresponding to different modulation frequencies is relatively altered substantially throughout the entire range of such frequencies, a detector to which the energy transmitted through said piezo-electric 10 device is supplied, and an audio amplifier associated with said detector including means for altering the amplitude of the wave-form energy corresponding to different modulation frequencies in the opposite sense, said last named means being 15 adapted to impart to said amplifier sharp cut-off effects at substantially 4800 cycles.

8. In a superheterodyne receiver provided with a first detector circuit adapted to produce in its output a band of frequencies including a desired 20 intermediate frequency carrier and its modulation side band frequencies, an intermediate frequency amplifier including at least one tube having means in its input to normally maintain a negative bias on the tube grid, a bridge circuit 25 coupled between the amplifier tube input and the detector output, said bridge including as an arm thereof a crystal resonant to said desired carrier, a second detector, an audio frequency amplifier including at least one tube, and a tuned path 30 shunted across said tube tuned to a period of substantially 4800 cycles.

9. A selecting system for radio receivers and the like adapted to receive incoming signal energy, such as is constituted by a modulated carrier wave, 35 comprising in combination, a signal interceptor and signal conveyer arrangement provided with output terminals, a resonator capacity bridge circuit provided with input terminals and output

terminals one arm of said bridge including a mechanical resonator device, said input terminals being connected to the first named output terminals, whereby energy intercepted by the interceptor is conveyed through the conveyer to the 5 resonant circuit, a detector and amplifier arrangement connected to the output terminals of the resonant circuit, said resonant circuit having such sharp frequency characteristics due to the resonator device that a portion of the desired signal 10 energy fed thereto from the interceptor conveyer arrangement is discriminated against to such an extent as to cause substantial distortion of the signals, means connected to the amplifier arrangement for giving to said amplifier predetermined distortion characteristics of such character that the portion of the desired signal energy discriminated against due to the resonant circuit is de-distorted to the extent that the portion of the desired signal discriminated against is brought 20 back so as to bear substantially its original relationship with respect to the remaining portion of the signal energy.

10. The system described in claim 9 wherein the resonant circuit comprises a piezo-electric 25 crystal bridge and wherein the input terminals are formed by two opposite points of the bridge and the output terminals are formed by two other opposite points of the bridge.

11. The system described in claim 9 wherein the means connected to the amplifier arrangement comprises a circuit shunted across the output of the amplifier which circuit is tuned to a frequency which closely approximates the frequency of the portion of the signal energy discriminated against. 30

WILLIAM S. BARDEN.
